UNITED STATES PATENT OFFICE

FRANK H. MONTREUIL, OF PHILADELPHIA, PENNSYLVANIA, ASSIGNOR TO WARREN WEBSTER & COMPANY, A CORPORATION OF NEW JERSEY

STEAM-HEATING SYSTEM

Application filed September 24, 1925. Serial No. 58,277.

My invention has for its object a simple and inexpensive means for heating a garage or other small building adjacent to but separated from a residence or main building 5 which is provided with a steam heating system, whereby the steam supply for heating the garage may be derived from the boiler of the heating system in the residence or main building and wherein the heating of the garage or other small building may be accomplished without danger of the water of condensation in the pipes or radiators becoming frozen.

It frequently happens that residences are 10 provided with small garages or other isolated out-buildings which require heat but do not warrant the installation of a separate distinct heating plant, and attempts have been made to supply the steam for heating 15 radiators or coils in the garage or out-building from the boiler in the residence or main building. Experience has demonstrated, however, that it is not feasible to employ an extension of the usual system of steam heating 20 employed in the residence or main building as a means of heating the garage or out-building as if it was an extra room. It has been found that such attempts have resulted 25 in the failure of the system to resist being frozen up in the cold weather, with the resulting destruction of piping and radiators.

The object of the present invention is to provide an arrangement of heaters and piping for the garage or out-building, to be operated from the same source of steam as is employed in the residence or main building, which will insure satisfactory circulation and at the same time be proof against freezing either as to the contents of the radiators 30 or the steam supply or return pipes.

My invention consists in a steam heating system employed in a residence or main building and comprising a boiler and a two-pipe system wherein the steam is supplied to 35 the radiators by one set of pipes and the water of condensation therefrom is returned by gravity through a second set of pipes and delivered to the boiler, combined with radiators in the garage or out-building coupled 40 with the boiler by piping so as to operate as

a one-pipe system, the water of condensation from said radiators returning to the boiler by gravity and the air liberated in the radiators being permitted to escape into the atmosphere through a suitable automatic 55 valve device which permits such escape of air but prevents the escape of steam and, preferably, also prevents an inflow of air.

The residence or building is heated by means of the usual two-pipe gravity system, preferably of the modulation type and under a normal predetermined differential across the radiators, whereas the garage is heated by a one-pipe system wherein the water of condensation returns through a pipe 60 buried in the ground sufficiently low to prevent freezing and delivers to the boiler by gravity, and wherein the steam is supplied to the one-pipe connection with the radiators in the garage or out-building (without a pressure differential across the radiators), whether the same is delivered through a buried supply and return pipe or through a separate boxed steam supply main in parallel connection with the water return pipe when the distance between the residence or main building and the garage or out-building is relatively 70 small and temperature conditions are not too severe.

My invention also comprehends details of construction which, together with the features above enumerated, are more fully described hereinafter and pointed out in the claims.

Referring to the drawings: Fig. 1 is a vertical section of a residence and a garage 85 equipped with heating apparatus embodying my invention; Fig. 2 is a similar view showing a modification of my invention; and Fig. 3 is a vertical section of the garage radiator air relief valve.

1 represents the residence or main building. 2 represents a steam boiler or generator suitable for generating steam of a pressure sufficient for the purposes of a gravity system of steam heating, such as may be required to properly heat a residence or main building. 3 is a steam main receiving steam from the boiler and provided with steam risers 4 leading to the radiators 5 in the different rooms of the building, and the steam supplied 95 100

to the radiators may be controlled by suitable valves 6. The water of condensation from the radiators passes therefrom downward through vertical return pipes 8 which connect into a return main 7 in the basement from which the water of condensation may pass to a receiver 10 in which a static head may be maintained and from which receiver said water is gradually delivered through a pipe 10^a and check valve 11^a into the lower part of the boiler 2. The radiators 5 are provided, at their discharge openings, with suitable automatic traps 9 which permit the passage of water and air into the return pipes 8, but restrict the passage of steam. A system of this character is well known as a two-pipe or gravity system and is adapted to operate under relatively low steam pressure, but employs a differential in pressure between the supply and return sides of the system to insure circulation and hence is provided with additional means embodied in the static head for positively returning the water of condensation to the boiler against boiler pressure.

12 represents a garage or out-building of relatively small size compared to the main building or residence and usually located at a short distance from the residence and built directly upon the ground. The room space therein is arranged relatively low with respect to the floors of the residence and more or less on a level with the basement in which the boiler is located. The radiator 13 arranged within the garage is best made in the form of a wall radiator and suspended at an elevation in the room space which will provide a static head in the return pipe composed of parts 16 and 17 from the radiator equivalent to the static head which would be required to return the water of condensation into the boiler by gravity in the residence or main building, said elevation of the radiator only being required when the garage floor is substantially at or below the water level in the boiler. If for any reason the floor level of the garage should be at a sufficient height above the water level in the boiler equivalent to the height of the static head required, then the radiator or heating unit might be supported directly from the floor. If, on the other hand, the floor of the garage was so low down that it was considerably below the water level in the boiler, it would then be necessary that this radiator or heating unit be elevated to approximately the upper part of the room space, even if adjacent the ceiling.

The radiator 13 in the garage is supplied with steam through the overhead pipe 14 which is suspended above the ground level and radiator and preferably boxed in. This steam supply main 14 is preferably inclined from its end which enters the garage and connected by a vertical pipe 15 leading down-

ward to form a connection with the water return pipe 16, the said pipes 15 and 16 having a branch connection 19 with the lower part of the radiator 13, the same being such that the water of condensation from the radiator will flow by gravity through said pipe 19 and into the return pipe 16, whereas the steam supplied to the radiator will pass from pipe 15 through said branch 19 into the radiator.

It will further be seen that the supply pipe 14, at its end in the residence or main building, has a downward branch 14^a connecting with the steam main 3 from the boiler; and this pipe 14^a may be extended downward as a drip pipe 18 and connected to the pipe 11^b (providing a connection from the return pipe 17 to the boiler) so that any water of condensation which flows backward from the pipe 14 will be transferred, by gravity, to the return side of the system.

The return pipe 17 connects by pipe 11^b with the lower part of the boiler 2 and a check valve 11^a is preferably inserted in said pipe 11^b between the boiler and the static head pipe 11^a, to permit the water of condensation to flow into the boiler by gravity but prevent the outward flow of the water from the boiler. In addition to the check valve 11^a, a check valve 11^c is also arranged in the pipe 11^b between the static head pipe 10^a and the drip pipe 18 to prevent flow of water from said static head pipe 10^a into the drip pipe as well as preventing it flowing back into the return pipe 17.

Referring further to the radiator 13 in the garage, the end thereof most distant from the steam supply connection 19 is provided with a vertical vent pipe 20 whose lower end is connected to the radiator a little above the possible level of the water of condensation therein which may accumulate when heating up the radiator, and the upper end of said vent pipe is provided with an automatic vent valve 21 (which may be of a thermostatic construction) which will permit the passage of air but prevent the passage of steam. The discharge from said thermostatic valve may pass into the atmosphere through a check valve 22 which is so arranged as to permit the escape of air from the system but prevent the inflow of air thereto, so that if there is a vacuum produced within the radiator, it may be maintained until overcome by the inflow of steam. The vent pipe 20 also is provided with a manually operable valve 23 by means of which the escape of air from the radiator may be controlled whereby the heating capacity of the radiator may be varied by air binding it to a greater or lesser extent, as desired, to limit the available space for the admission of steam.

It will be seen from the foregoing description that, while a predetermined differential in pressure is provided across the radiators in

the two-pipe gravity system employed for heating the residence or main building and suitable static head or other equivalent means in the returns is required to insure the delivery of the water of condensation into the boiler against the pressure therein, the radiator in the garage is operated as a one-pipe system and has no pressure differential between the intake for steam and the outlet for the water of condensation, and consequently, provision is made with the garage radiator and piping as will permit the supply of the steam to and delivery of the water from the radiator, notwithstanding the differential employed in the two-pipe system of which the boiler forms a part. This is accomplished by reason of the fact that the steam main 14 and the return main 17 are coupled together at their respective ends whereby the pressures in the two are equal, said coupled mains being jointly connected with the radiator through one opening, thereby permitting both the inflow of steam and the outflow of water. While there is no differential pressure across the radiator, a static head, however, must be provided in the pipe 16 which is sufficient to insure the return of the water of condensation which may pass from the radiator 13 into the boiler against the steam pressure therein, but ordinarily this will be insured if there is only one or two inches of static head above the water level or just sufficient to overcome the friction and lift the check valves 11^a and 11 in passing through the return pipes 16 and 17 into the boiler, because, in this case, we have the normal steam pressure of the boiler upon the top of the static head in the pipe 16. By reason of the construction shown, it is manifest that no water of condensation can remain in the piping at any level above the level of the water in the boiler, unless a partial vacuum is produced in the radiator 13, and this is, of course, possible under certain conditions of operation such as when first turning on the steam at valve 14^b located in the main building. When this is done, the steam passes by pipes 14 and 15 into the radiators where it is condensed and, if the condensation is very rapid as would occur in extremely cold weather, a vacuum is produced in the radiator and will be maintained so long as the radiator retains capacity for rapid condensation, because the check valve 22 automatically closes and prevents inflow of air to break the vacuum. However, when the radiator becomes sufficiently heated the power to maintain the vacuum is destroyed by the inflowing of more steam and thereafter the radiator operates normally.

Assuming that less than the full heating capacity of the radiator is required, the hand valve 23 may be closed, and in this event, the air liberated from the steam will be retained in the radiator and may be accumulated

therein to the desired degree. When operating in this manner, the steam enters and fills the lower part of the radiator and the water of condensation continually flows off by gravity. If the accumulations of air increase to such an extent that insufficient heat is provided, the valve 23 may be opened until the quantity of air is reduced to that desired and the radiator thus given an increased capacity to the extent necessary.

It is further to be understood that where the garage is at a distance from the residence where the boiler is situated and steam is first turned on to the garage in cold weather, there is liability of the steam pressure in the pipe 14 being so reduced on its way to the garage that very little pressure occurs at the radiator 13. When this happens, no matter what is the condition within the radiator 13, there will be insufficient counter-balancing steam pressure upon the return pipe 16 and consequently the water which may be in the return pipe 17 will be forced upward into the upright pipe 16 by reason of the pressure on the end of the pipe 17 next to the boiler. The pipe 16 must extend above the water level in the boiler, to provide a sufficient static head (without flooding the radiator 13 or necessity of shutting off the steam supply thereto) which, with such steam pressure as exists, will balance the steam pressure in the boiler. In other words, the static head which is automatically made effective in the pipe 16 compensates for the loss of the steam pressure in the pipe 15 with which it is connected. Because of this automatic operation and the maintenance of the radiators 13 clear of water, the same are insured against freezing. There is no water in the steam supply pipes 14 and 15, even though there should be a maximum drop in steam pressure; and as the water return pipe 17 is buried in the ground below freezing level, the danger to said pipe is overcome. If the radiator in the garage is to be shut off, when the garage is not in use, the hand valve 23 is closed. If the valve 23 is wholly shut off, the accumulations of air in the radiator would ultimately prevent the inflow of steam and the radiator would become cold and remain so. If the valve 23 were very slightly opened, so as to permit escape of some air while maintaining sufficient air in the radiator to air-bind it to the desired degree, the garage may be heated to suit atmospheric conditions. In the construction shown, the arrangement is such that the radiator 13 is operated as in a one-pipe system, but is at all times clear of water and controlled wholly by the extent of air-binding permitted.

In the modification of my invention, shown in Fig. 2, the garage is located at a considerable distance from the building wherein the boiler is located, and under conditions where it is not convenient to employ an overhead

steam line, as at 14 and 15 in Fig. 1. I therefore employ a modified construction as follows: The supply of steam and the outflow of water of condensation, with respect to the radiator 13 in the garage, take place at its lower part as in Fig. 1, and includes the steam mains 16^a and 17^a, the latter leading underground from the garage and on a slight incline into the cellar of the building where the boiler 2 is located. The connection between the said main 17^a and the boiler is formed by an overhead pipe 24 for the supply of steam and pipe 11^b and check valve 11^a for the passage of water of condensation to the boiler, the latter acting as a drip from the steam supply main 17^a which receives its steam supply from the pipe 24 connecting with the boiler. The lower end of the steam main 17^a is approximately twelve inches or thereabouts above the normal level of the water in the boiler, so as to be capable of providing at least that much of a static head in pipe 11^b from the drip or condensate from the radiator 13 and main 17^a without shutting off the steam supply to the main 17^a by valve 14^c. In the garage, the radiator 13 is provided with a vent pipe 20 having the thermostatic air valve 21 and the check valve 22, all as shown in Fig. 1, and in addition thereto, it is also provided with a hand control valve 23 whereby capacity is provided for producing air binding of this radiator to the extent desired, when less than the maximum temperature is required. As the main 17^a is required to handle both the water of condensation and the steam in connection with the radiator in the garage, it is manifest that this pipe should be of larger diameter than is required for the water return pipe 17 in the apparatus shown in Fig. 1; and it is also understood that the radiator in the garage should be arranged at an elevation which is sufficient to insure the flow of water of condensation back to the boiler under a sufficient static head to insure its proper return thereto, even when the valve 14^c is closed.

It will now be apparent that I have devised a novel and useful means which embodies the features of advantage enumerated as desirable and have described them in that particularity which I deem to be the best exposition of my invention, and while I have shown and described the preferred embodiment thereof which has been found in practice to give satisfactory and reliable results, I do not restrict myself to the minor or secondary details as the same are susceptible of modification without departing from the spirit or scope of the invention.

Having now described my invention, what I claim and desire to secure by Letters Patent is:

1. In a heating system, a main building equipped with a two-pipe gravity steam heat-

ing system including a boiler, risers, return pipes and radiators and wherein the water of condensation is automatically returned to the boiler under a maintained differential pressure across the radiators plus a static head which, together with the differential pressure is substantially equal to the boiler pressure and said radiators each having a separate control valve to regulate the supply of steam thereto, in combination with a separate building at a distance from the main building, and heating means for said separate building consisting of a radiator arranged at an elevation above the water level in the boiler in the main building, normally open steam supply and water return connections between the lower part of the radiator in the separate building and respectively in communication with the steam and water spaces of the boiler in the main building to normally maintain steam in the radiator of the separate building at substantially boiler pressure, a portion of said steam supply and water return connections including a pipe from the lower part of the radiator and embedded in the ground with a downward incline toward the boiler of the main building and through which return water of condensation flows, and means in communication with the interior of the radiator in the separate building for insuring regulated communication thereof with the atmosphere.

2. The invention according to claim 1, wherein further, the normally open steam supply connection with the radiator in the separate building is made as a steam pipe extending above the ground level and water level of the boiler and provided with a downwardly extending part in direct communication with the embedded water return pipe at a point adjacent to the lower part of the radiator and whereby the water of condensation therefrom flows into the embedded water return pipe.

In testimony of which invention, I hereunto set my hand.

FRANK H. MONTREUIL.
